Primary Examiner — Robert A Delehanty(74) Attorney, Agent, or Firm — Mark Terry(57) CLAIM

The ornamental design for a bidet attachment for a toilet, as shown and described.

DESCRIPTION

FIG. 1 is a top perspective view of a bidet attachment for a toilet, showing the new design;

FIG. 2 is a left side perspective view thereof;

FIG. 3 is a front view thereof;

FIG. 4 is a top view thereof;

FIG. 5 is a rear view thereof;

FIG. 6 is a bottom view thereof;

FIG. 7 is a left side view thereof; and,

FIG. 8 is a right side view thereof.

The uniformly dashed lines shown in the drawings illustrate portions of the bidet attachment for a toilet which form no part of the claimed design.

1 Claim, 3 Drawing Sheets(56)
